C. E. BERTELS

FILE

Filed Oct. 8, 1927

UNITED STATES PATENT OFFICE.

CHARLES E. BERTELS, OF LONG BEACH, CALIFORNIA, ASSIGNOR OF ONE-HALF TO
JOHN P. BENNING, OF TRUCKSVILLE, PENNSYLVANIA.

FILE.

Application filed October 8, 1927. Serial No. 224,980.

This invention relates to files and has for an important object thereof the provision of a flexible file of such construction that it may be very conveniently employed for treating 5 round surfaces of different diameters.

A more specific object of the invention is to produce a file formed in a plurality of relatively short sections which are pivotally connected with one another in such manner that 10 adjacent sections may be relatively positioned to contact curved surfaces of different diameters.

The invention further resides in the method of constructing and connecting the sections.

These and other objects I attain by the construction shown in the accompanying drawing, wherein for the purpose of illustration is shown a preferred embodiment of my in- 20 vention and wherein:—

Figure 1 is a side elevation of a file constructed in accordance with my invention;

Figure 2 is a fragmentary plan view thereof;

Figure 3 is a section on the line 3—3 of Figure 2;

Figure 4 is a fragmentary plan view showing a slightly modified form of file section.

Referring now more particularly to the 30 drawing, the numeral 10 generally designates handles to which are linked at 11 the ends of a file 12 formed in a plurality of sections 13. The sections 13 may be formed in a number of different ways of which two are illustrated. In Figures 1 and 2, the file sections each comprise a plurality of leaves 14, the inner faces of which are provided with file or shallow saw teeth. The blades are arranged in spaced relation to one another and are 35 mounted at their ends upon pins 15, which form the pivots between the sections, the blades of each section being staggered with relation to the adjacent sections and inter-

digitated therewith. The endmost pins 15 serve to connect the ends of the file band 12 45 to the links 11, the opposite ends of these links being connected to the handle by pins 16. In Figure 4, the file sections are each in the form of a block 17, one surface of which is treated to form a file face 18 and the ends 50 of which are provided with ears 19 adapted to interdigitate with the ears of adjacent sections and be pivoted thereto by pins 20.

It will be obvious that by either of the constructions referred to, the band produced will 55 be flexible and may be readily fitted about a curved surface and reciprocated therethrough with relation to the handles 10. It will also be obvious that while I have described a structure wherein one face only of 60 each of the sections is formed as a file, opposite faces thereof may be so constructed, if desired.

Since the constructions illustrated are capable of a certain range of change and modification without materially departing from the spirit of the invention, I do not limit myself to such specific structure except as hereinafter claimed.

I claim:—

A file comprising a pair of handles and a flexible band connecting the same, said flexible band being composed of sections each comprising a plurality of flat leaves having file teeth upon at least one face thereof, said leaves being spaced from one another transversely of the sections, the leaves of one section being interdigitated with the leaves of the adjacent sections and pins extended 75 through the interdigitated portions of the 80 leaves to pivotally connect the same and maintain the leaves in assembled relation.

In testimony whereof I hereunto affix my signature.

CHARLES E. BERTELS.
